UNITED STATES PATENT OFFICE.

EDWARD TANNEWITZ, OF GRAND RAPIDS, MICHIGAN.

TURNING-LATHE.

No. 895,699.

Specification of Letters Patent.

Patented Aug. 11, 1908.

Original application filed May 14, 1906, Serial No. 316,770. Divided and this application filed July 1, 1907.
Serial No. 381,595.

To all whom it may concern:

Be it known that I, EDWARD TANNEWITZ, citizen of the United States, residing at the city of Grand Rapids, county of Kent, State 5 of Michigan, have invented certain new and useful Improvements in Turning-Lathes, of which the following is a specification.

This invention relates to improvements in turning lathes.

10 It relates particularly to an improved turning lathe for turning round rods.

It is frequently the case that stock used for rods, such as spindles, dowels, dowel rods, or the like, is irregular or varying in thickness. This is especially the case when the stock is ripped off from planks.

15 It is the main object of this invention to provide an improved turning lathe adapted to operate upon such strips of irregular or varying thickness.

Further objects, and objects relating to details of construction, will definitely appear from the detailed description to follow.

20 I accomplish the objects of my invention by the devices and means described in the following specification.

The invention is clearly defined and pointed out in the claims.

25 A structure embodying the features of my invention is clearly illustrated in the accompanying drawing, forming a part of this specification, in which,

30 Figure 1 is a longitudinal central section, through a structure embodying the features 35 of my invention, taken on a line corresponding to line 1—1 of Fig. 2. Fig. 2 is a detail transverse section taken on a line corresponding to line 2—2 of Fig. 1. Fig. 3 is a detail longitudinal section through the stock 40 holding sleeve 9, taken on a line corresponding to line 3—3 of Fig. 4. Fig. 4 is a cross section thereof, taken on a line corresponding to line 4—4 of Fig. 3.

45 In the drawing, the sectional views are taken looking in the direction of the little arrows at the ends of the section lines, and similar numerals of reference refer to similar parts throughout the several views.

50 Referring to the drawing, 1 represents the frame of the machine which is provided with bearings 2—2 for the arbor 3 of the cutter head. The arbor is provided with a pulley 4. The arbor 3 is hollow and is interiorly threaded at its forward end to receive the 55 cutter head 5. The cutter head is provided

with a conical mouth or chamber 6 at its inner end into which the conical delivery end 10 of the work holder 9 projects.

The mouth 6 of the cutter head is extended or continued into a cylindrical work support 60 7. The stock holder 9 is arranged through the hollow arbor 3 of the cutter head, and is supported at its outer end by the bracket 15 on the frame, the work holder being provided at its rear end with a hub-like enlargement 14, adapted to fit into the bracket and thereby rigidly support the work holder. The work holder is provided with a longitudinal stock opening 11, the stock opening being oblong in cross section and out of center 70 with the holder sleeve 9, so that the opening is out of center with the cutter head. Within the stock opening is a blade spring 12 secured to the wall thereof by a suitable rivet, as 13, the spring being secured at its rear end, 75 and its free end projecting forwardly to the delivery end of the work holder. This spring holds the stock downwardly in the work holder, so that it is properly centered and delivered to the cutter head. As the work 80 holder extends into the cutter, it is supported practically to the point where it is acted upon by the cutter head, so that it is not likely to be twisted off, although it may be of small diameter. This enables the working up of 85 cross grain "trash" or "shaky" stock and also of short pieces. The work holder is adapted to receive strips of varying thickness, and thus the necessity of running them through a sizing saw is obviated.

90 The structure is very simple and at the same time is entirely effective for the purpose.

Having thus described my invention, what I claim as new and desire to secure by Letters Patent is:

1. In a turning lathe, the combination of a revolvably mounted cutter head having a conical mouth at its rear end and a cylindrical work support at its forward end; a non-revolvble stock holder having a conical delivery end arranged in the said conical mouth of said cutter head, and a stock opening therethrough, said stock opening being oblong in cross section and having two opposed sides 100 spaced to correspond to one cross dimension of the stock; and a blade spring arranged in said stock opening of said stock holder with its rear end secured to the wall thereof and its free end extending forwardly to the de- 110

- livery end of the stock-holder and acting parallel to said opposed sides and towards an intermediate fixed side, said cutter head and work support being centered relative to that portion of the stock opening described by a square having dimensions equal to the distance between the said opposed sides, the said opposed sides and said intermediate fixed side forming three sides of the square, wherefore stock of varying width is properly centered and supported to be acted upon by said cutter head.
2. In a turning lathe, the combination of a cutter head; a stock holder having a stock opening therethrough, said stock opening being oblong in cross section and having two opposed sides spaced to correspond to one cross dimension of the stock; and a blade spring arranged in said stock opening of said stock holder with its rear end secured to the wall thereof and its free end extending forwardly to the delivery end of the stockholder and acting parallel to said opposed sides and
- towards an intermediate fixed side, said opposed and said intermediate sides forming unyielding supports for the stock.
3. In a turning lathe, the combination of a mounted cutter head; a stock holder having a stock opening therethrough, said stock opening being oblong in cross section and having two opposed sides spaced to correspond to one cross dimension of the stock; and a spring arranged in said stock opening of said stock holder, to act parallel to said opposed sides and towards an intermediate fixed side, said opposed and intermediate sides forming unyielding supports for the stock.

In witness whereof, I have hereunto set my hand and seal in the presence of two witnesses.

EDWARD TANNEWITZ. [L. S.]
